UNITED STATES PATENT OFFICE.

HERMAN V. HODGES, OF SAN GABRIEL, CALIFORNIA.

LIGHT ATTACHMENT FOR CLIPPERS.

Application filed January 24, 1924, Serial No. 688,123.

To all whom it may concern:

Be it known that I, HERMAN V. HODGES, a citizen of the United States, residing at San Gabriel, in the county of Los Angeles 5 and State of California, have invented new and useful Improvements in Light Attachments for Clippers, of which the following is a specification.

My invention relates to light attachments 10 for clippers, and consists of the novel features herein shown, described and claimed.

My principal object is to make a light fixture for attachment to a hair or wool clipper, and adapted for throwing the light 15 downwardly upon the cutter and forwardly in front of the cutter.

Another object of my invention is to make a light fixture for attachment to a hair or wool clipper, the clipper being operated by 20 a flexible shaft from a motor and the light fixture being operated from the same line as the motor by a branch line run through a transformer and along the flexible shaft.

Another object is to make a light fixture 25 having a spring clip adapted to snap onto and off from the thumb nut of a clipper.

Figure 1 is a side elevation of a hair or wool clipper provided with a light attachment in accordance with the principles of 30 my invention, the flexible shaft and light line being broken away.

Fig. 2 is a front perspective of the light attachment and the spring clip engaging the thumb nut of the clipper, the clipper being 35 omitted.

Fig. 3 is a perspective of the spring clip shown in Figs. 1 and 2.

Fig. 4 is an electric diagram showing how 40 the light attachment is operated from the same line that operates the motor to drive the flexible shaft of the clipper.

The clipper 1, shown in Fig. 1, has a clamping plate 2 held in place by a stud bolt 3 anchored to the body of the clipper 45 and extending through the plate 2 and a thumb nut 4 upon the stud bolt. I place an expansive coil spring 5 upon the bolt 3 against the plate 2 under the nut 4 so as to elevate the nut for convenience in applying the light attachment.

The lamp bulb 6 is screwed into a standard socket 7 and the spring clip 8 is soldered to one side of the socket 7 and is adapted to embrace the nut 4.

55 The reflector 9 is made of a single piece of soft metal and consists of the ferrule 10,

the housing 11, and the reflecting portion 12. The electric cord 13 is passed through the ferrule 10 some distance and then properly connected to the socket 7 and pulled 60 backwardly to bring the socket 7 into the housing 11, and so that the ferrule 10 covers the joint between the cord 13 and the socket 7. The reflecting portion 12 is flared and curved to substantially a half circle to properly surround the globe 6 and throw the light upon the cutter 14 and in front of the cutter.

The spring clip 8 is formed of a single piece of wire, the center of the wire being 70 bent to form the U-shaped attaching portion 15, arms 16 and 17 extending laterally from the portion 15, the curved bars 18 and 19 extending from the arms 16 and 17, the spaced return bends 20 and 21 at the ends 75 of the bars 18 and 19, the second bars 22 and 23 parallel with the bars 18 and 19 and spaced therefrom, and the end attaching fingers 24 and 25 within the U-shaped attaching portion 15. The attaching portion 15 80 and the attaching fingers 24 and 25 are soldered to the lower side of the socket 7 and the spring clip is applied by placing the rim of the thumb nut 4 between the return bends 20 and 21 and forcing the return 85 bends apart until they pass the largest diameter of the nut and the rim of the nut fits between the arms 19 and 23 and 18 and 22, as shown in Fig. 2.

Referring to the diagram shown in Fig. 90 4, the house line has the conductors 26 and 27 connected to the generator 28, and the branch lines 29 and 30 operate the motor 31; the clipper 1 is connected to the motor 31 by a flexible shaft 32. The branch lines 33 95 and 34 lead from the lines 29 and 30 to a transformer 35, and the lines 36 and 37 run along the flexible shaft 32 to the lamp 6. A sheath 38 of protecting material covers the flexible shaft 32 and the wires 36 and 37 100 from the motor to the clipper, so that the electric wires are handled along with the shaft.

Various changes may be made without departing from the spirit and scope of my invention as claimed.

I claim:

1. A light attachment for clippers comprising a lamp socket, a lamp in the socket, a spring clip secured to the socket and adapted to engage the thumb nut of a clipper, an electric cord connected to the socket,

and a lamp reflector comprising a ferrule fitting the electric cord, a housing fitting the lamp socket and a reflecting portion surrounding the upper part of the lamp.

- 5 2. In a light attachment for clippers or the like, a spring clip formed of a single piece of wire having a center U-shaped bend, curved bars extending from the U-shaped bend, return bends at the ends of the bars, 10 second bars parallel to the first mentioned bars, fingers extending therefrom into the U-shaped bend, a lamp socket, and means to attach the clip to the lamp socket.
3. In a light attachment for clippers or

the like, a spring clip formed of a single 15 piece of wire having a center U-shaped bend, arms extending laterally from the U-shaped bend, curved bars extending from the arms, spaced return bends at the ends of the bars, second bars parallel with the first bars and 20 spaced therefrom, fingers extending from the second bars into the U-shaped bend, a lamp socket, and means to connect the U-shaped bend and fingers to the socket.

In testimony whereof I have signed my 25 name to this specification.

H. V. HODGES.
